C. A. MUTISPAUGH

LATCH

Filed May 19, 1925

FIG. 1.

FIG. 2.

FIG. 3.

Inventor

C. A. Mutispaugh

By *William Talbot*
Attorney

UNITED STATES PATENT OFFICE.

CHARLES A. MUTISPAUGH, OF PLANT CITY, FLORIDA.

LATCH.

Application filed May 19, 1925. Serial No. 31,361.

The object of the invention is primarily to provide a device adapted for use in connection with doors, gates and the like so that the same be held latched in open position 5 to preclude swinging as a result of wind pressure and other causes.

With this object in view, the invention consists in a construction and combination of parts of which a preferred embodiment 10 is illustrated in the accompanying drawings, wherein:

Figure 1 is a front elevational view showing the invention applied in operative position.

15 Figure 2 is an enlarged detail sectional view on the plane indicated by the line 2—2 of Figure 1.

Figure 3 is a view similar to Figure 2 but illustrating the latch member in the position 20 of releasing a gate or door preparatory to closing the latter.

Designed for engagement with a gate or door, such as that indicated at 10 in the drawings, the invention comprises a swinging member 11 pivotally supported in a bracket 12, the latter being mounted in a plane below the plane of the lower edge of the door. The swinging member 11 is provided with a tapered nose 14 disposed at one 25 extremity and a tail plate 15 at the other extremity, the member having a throat 16 just behind the nose to provide a hook for engaging the lower edge of the door.

In the opening movement of the door, the 30 latter is swung against the upper forward edge of the tail plate, being provided with an impact plate 17 to preclude wear when the door or gate is of wood. The impact of the door with the tail plate rocks the 35 swinging member on its pivot and when the remote edge 18 of the tail plate engages the 40 surface of the means supporting the latch,

the nose portion of the swinging member is elevated and the lower edge of the door is disposed within the throat 16. 45

It is not essential that the swinging member work freely to a successful operation of the device. If it does not move freely enough on its pivotal connection to permit it to drop when in disengaged position—and it is preferable that it do not move so freely—it will, if the nose portion be depressed at the time of opening the door, be actuated by the engagement of the impact plate 17 with the edge of the tail plate. If the nose be elevated when the door is opened, the impact plate will engage the inclined edge of the nose and depress the latter, thus swinging the tail plate upwardly, but when the latter is engaged by the impact plate, the edge of the door will have passed the rear end of the nose and the latter will be elevated into obstructing relation with the lower edge of the door. 55

The door carries a plate 19 of a contour corresponding to the throat 16 for seating in the latter when the door is in open position and engaged by the swinging member. 60

The invention having been described, what is claimed as new and useful is:

A device for the purpose indicated comprising, in combination with a swinging door, a swinging member having a pivotal point below the lower edge of the door, and a forward nose and adjacent throat and a tail plate for terminal abutting engagement with the rear face of the door, and a plate mounted on the forward face of the door and of a cross sectional contour corresponding with said throat and engaging the latter in the closed position of the door. 75 80

In testimony whereof he affixes his signature.

CHARLES A. MUTISPAUGH.
